UNITED STATES PATENT OFFICE.

SAMUEL S. AMDURSKY, OF ROCHESTER, NEW YORK, ASSIGNOR TO THE TAYLOR INSTRUMENT COMPANIES, OF ROCHESTER, NEW YORK, A CORPORATION OF NEW YORK.

APPARATUS FOR REGULATING WAX-SWEATING SYSTEMS.

Application filed October 9, 1923. Serial No. 667,499.

This invention relates to processes and apparatus for regulating wax sweating systems in which the crude or slack paraffin wax or the like is subjected to a heat treatment for progressively melting out the contained oil by-products and finally the purified wax or scale having a desired melting point. The chief object of the invention is to provide an efficient process and apparatus for accomplishing this result with a maximum percentage yield of purified wax or scale having a minimum oil content with the least practical expenditure of time, heat and labor.

To these and other ends the invention resides in certain improvements and combinations of parts all as will be hereinafter more fully described, the novel features being pointed out in the claims at the end of the specification.

In the drawings:

Fig. 1 is a sectional elevation illustrating apparatus embodying and employed in carrying out the present invention;

Fig. 2 is an enlarged sectional view of one of the sweating pans on the line 2^a—2^a in Fig. 1;

Fig. 3 is a sectional elevation on the line 3^a—3^a in Fig. 1 and

Fig. 4 is an enlarged sectional elevation on the line 4^a—4^a in Fig. 1.

Similar reference numerals throughout the several views indicate the same parts.

The invention is carried out and embodied in the present instance, by way of illustration, in conjunction with a common form of wax sweating apparatus shown in the drawings as comprising, preferably, a containing means, or sweating house proper, shown at 5, Fig. 1 and spaced therefrom an apparatus house 6. The sweating house is constructed as a simple enclosure or room adapted to be made substantially air tight by closing all openings such as doors and windows and located therein are one or more and preferably, a series of receptacles in the nature of metal pans 7 which may be conveniently stacked one above the other in spaced relation as shown on supporting standards 8 at the corners. The pans may conveniently have a size approximately 20 feet wide by 60 feet long and about 10 inches deep, with a dished bottom draining through a discharge outlet 9, such outlets being conveniently connected by piping (not shown)

with a common discharge. Supported in any suitable manner between the top and bottom of each pan is a screen partition 10, above which is a series of temperature controlling coils 11 preferably arranged in a common plane as shown and forming a portion of a temperature controlling means comprising a common supply line 12 having individual branches 13 for the different pans for supplying a temperature controlling medium, such for example as cold water or hot water or steam, to the heating coils. The returns from the latter are united by piping connections of any suitable arrangement, omitted from the drawings for the purpose of clearness, with a common return pipe 14, the temperature controlling medium being circulated through the pipes 12 and 14 and the pan coils 11 by means hereafter described. Means are also provided for heating the sweating house, such, for example, as the radiators 15 supplied with a temperature controlling medium through a common supply pipe 16 and having a common discharge pipe 17. Steam is employed in the present instance for heating the sweating house by means of these radiators and is supplied to the latter as hereafter described.

With the use of apparatus such as described above, the sweating process is begun by filling the pans 7 with cold water to the level of screens 10 for which purpose a water supply nozzle may be provided if desired for each pan. The crude or slack wax which may for present purposes be considered as of the variety containing paraffin to be extracted, is heated above its melting point and then poured into the pans in which it floats above the surface of the water at the level of the screen 10, sufficient of the material being allowed to flow into each pan to cover the coils 11. In this manner, the crude material is disposed in a body, cake or plate of extended surface exposure and molded about the coils so that the latter are distributed interiorly throughout the body of material. Cold water is then circulated through the coils 11 and the doors and other openings of the sweating house opened to cool and solidify the crude material in the pans. To expedite this result a cooling medium may obviously be circulated through the radiators 15 if so desired.

When the crude slack has thus been reduced to a more or less solid state to pre-

vent it from flowing through the screen 10, the water in the pan below the screen is drained off through the outlet 9 and the material is ready for the heating treatment.

5 The sweating house door or other openings are then closed and a heating medium such for example as hot water is circulated through the pan coils 11 to heat the material, while the sweating house is heated by the circulation of steam through the radiators 15. The body of crude or slack wax in each pan is thus uniformly heated throughout interiorly by the coils and exteriorly by the heating of the room, with the result that the 15 oils contained in the material begin to melt out and drain to the bottom of each pan and through its outlet 9. In the production of paraffin an oil known as "foots oil" is first obtained and collected in a suitable vessel, 20 its temperature being tested from time to time, and when the latter reaches a predetermined degree as, say, 80 degrees F., the drainage or "drip" is diverted to another container for collecting oil of the next grade 25 as for example, the paraffin by-product known as crude scale or rerun slack wax. The temperature of this is similarly tested until a degree is reached corresponding to the upper limit of its melting point and the 30 lower limit of the melting point of the purified scale or paraffin when the drainage is again diverted. The heating process is continued and the drainage collected in a receiver for the paraffin which is then melted 35 out of the pans.

The process thus involves the progressive melting out from the cake of crude material of the oils of lower melting point contained in and finely distributed in cells or pores 40 throughout the cake and it has been found that in order to extract a maximum percentage of the oil the temperature of the crude material must be raised very gradually and uniformly throughout. Any sudden or excessive increase in the temperature tends to 45 melt out some of the paraffin and in addition tends to close up or seal the oil cells to such an extent that the final product contains a relatively high percentage of oil. In addition such unnecessary increases in temperature involve the waste of steam. On the other hand if the temperatures are lowered 50 the process is retarded and the material in the pans is chilled and its cells closed thereby arresting the escape of oil from the interior.

55 It has also been found that the rate of transfer of heat between the coils in the pans and the material molded about them in intimate contact is considerably higher than between the heated atmosphere of the room and the external surface of the material. This is particularly true at the beginning 60 of the heat treatment when the thickness and 65 solidity of the material cake is greatest. As

the thickness of the cake diminishes and its body becomes honeycombed with the melting out of the oil, the difference in the rate of transfer of heat diminishes and the temperature of the coils should be gradually 70 raised until at the end of the process it is nearly equal to that of the room. The temperatures of the coils and of the room are thus gradually increased in relatively converging relation from a temperature difference 75 at the start of the process of about ten degrees to a final difference of about two degrees, the temperature of the coils in the pans commonly varying for example from about 94 degrees Fahrenheit at the start to 80 about 120 degrees at the end of the process. The above method carries the crude material uniformly throughout its body through a range of temperatures such that the contained oils are progressively melted out at a 85 maximum rate made possible by the uniform maintenance of the body in a condition in which the oil cells or pores are kept open to facilitate its escape from the mass. Such a result can however, only be accomplished by 90 a very delicate and automatic regulation of the heating process, for which purpose the invention comprises also the following apparatus in addition to that described above. Located within the apparatus house 6 is a 95 water drum 18 with which is connected the supply pipe 12 leading to the coils in the pan. The return pipe 14 from the latter is also connected with the drum and a suitable pump 19 is located in the system, in the present instance in the line 12 for maintaining a circulation of the water through the coils. The water in drum 18 is heated by the injection of steam supplied through a pipe 20 controlled by an automatic valve 21 preferably of the well known diaphragm variety operated by fluid pressure supplied through a pipe 22 leading from a regulating device 23. The latter may be of any suitable or well known type comprising combined time 100 and temperature responsive mechanism controlling relay means for operating the valves, such for example as that disclosed in the co-pending application of Harry Y. Norwood, Ser. No. 521,222 filed Dec. 9, 1921, 105 for time control regulating apparatus. Apparatus of this general type is now well known so that a detailed description of the same appears superfluous further than to state that it comprises a time train and thermostatic means conjointly controlling an operating relay such as the fluid pressure system shown. Fluid pressure is supplied to the device through a pipe line 24 from a suitable source of pressure such as the drum 110 25 and the thermostatic means for controlling the pressure in the pipe line 22 and operating valve 21 comprises a thermometer bulb 23a located in the pipe 14 and connected 115 with the device by a capillary tube 26. By 120

125 130

this means the temperature of the water supplied to the coils in the pans is accurately controlled by controlling the supply of steam to the drum 18 so that the coils may be given a temperature maintained or varied as desired during the process.

The regulating apparatus comprises also, in combination with its timing mechanism, thermostatic means having a thermometer bulb 27 preferably of the known capillary variety extended through the sweating room 5 to measure the average temperature therein, and operating to control an air line 28 leading to a diaphragm valve 29 in the pipe 16 supplying steam to the radiators 15. By this means the temperature of the sweating room may be accurately regulated throughout the process as desired. By employing different cam or other actuating parts in the regulator timing mechanism for the pan coils and room heating means, respectively, as well understood in the art, the temperatures attained by these parts may be regulated in the relatively converging relation already described for efficiently accomplishing the desired result.

At 30, Fig. 4 is a known variety of pressure regulator comprising a diaphragm valve controlling the steam supply line and connected by a pipe 31 with the fluid pressure line 24. A second connection 31^a transmits the pressure of the steam line to the pressure regulator for automatically regulating the pressure in the steam connection 20 for heating the drum 18 and also for automatically shutting off the supply of steam entirely in case of failure of the fluid pressure supply for operating the regulator relay 22. Similarly the line 16 for supplying steam to the radiators of the sweating room is controlled by a diaphragm valve 32 having a fluid pressure connection 33 with the main fluid pressure supply line 24 for shutting off the supply of steam to the radiators 15 also in case of failure in the fluid pressure supply. At 34 is a water "make-up" line for the drum.

In the operation of the apparatus, after the crude material in fluid condition is poured into the pans as described above, cold water from drum 18, or from a different source of supply, if so desired, is circulated through the pan coils to cool the material. When the latter has become solidified, the water drained from the pans and the water in drum 18 heated by the supply of steam thereto, hot water is then supplied to the pan coils and steam to the radiators 15 to start the heat treatment. The latter is then

continued automatically by the apparatus as 60 already described in connection with the description of the process.

The invention thus provides also a practical and effective apparatus adapted to automatically carry out the above method in a 65 reliable and accurate manner with a saving in time, heat, energy and labor as well as an improvement in the quality of the products not heretofore attained.

I claim as my invention:

1. In apparatus for heat-treating wax, the combination with an open container for receiving the wax to be treated, of means for confining the atmosphere surrounding the container, heating means arranged to distribute heat through a body of wax occupying the container, means for supplying heat to the atmosphere surrounding the container, means for separately controlling the temperature in said heat distributing means and 80 the temperature of the atmosphere surrounding the container, and means for independently operating said controlling means to gradually increase the temperature in said heat-distributing means and the temperature 85 of the atmosphere surrounding the container at different rates.

2. In apparatus for heat-treating wax, the combination with an open container for receiving the wax to be treated, of means for confining the atmosphere surrounding the container, means arranged to distribute heat through a body of wax occupying the container, means supplying heat to the atmosphere surrounding the container, and means for automatically regulating the temperature of said heat distributing means and the temperature of the atmosphere surrounding the container, operative to increase the temperature of the heat distributing means at a greater rate than the temperature of the surrounding atmosphere.

3. In apparatus for heat-treating wax, the combination with an open container for receiving wax to be treated, of means for confining the atmosphere surrounding the container, means within the container arranged to distribute heat through a body of wax occupying the container, means for supplying heat to the atmosphere surrounding the container, and time-controlled means for automatically regulating the temperature conditions within and without the container, operative to increase the temperature within the container at a greater rate than the temperature of the atmosphere surrounding the container.

SAMUEL S. AMDURSKY.
